UNITED STATES PATENT OFFICE.

GEORGE F. CASS, OF CHICAGO, ILLINOIS, ASSIGNOR TO HIMSELF AND HUGH WHITE, OF SAME PLACE.

NAILING-MACHINE.

SPECIFICATION forming part of Letters Patent No. 307,912, dated November 11, 1884.

Application filed December 10, 1883. (No model.)

To all whom it may concern:

Be it known that I, GEORGE F. CASS, a citizen of the United States, residing in Chicago, in the county of Cook and State of Illinois, have invented a new and useful Improvement in Heel-Nailing Machines, of which the following is a specification.

My invention relates to devices for reciprocating the cross-head of heel-nailing machines from the crank-arm, which is driven continuously.

In the accompanying drawings, which form a part of this specification, and in which similar letters of reference indicate like parts wherever shown, Figure 1 is a side elevation of that portion of a heel-nailing machine to which my invention is applied. Fig. 2 is a plan view of the same. Fig. 3 is an elevation looking from the line 3 3 of Fig. 1. Fig. 4 is an enlarged section on line 4 4 of Fig. 2, and Fig. 5 is a detail perspective view of the lever and ratchet-bar.

In the drawings, A represents the frame of the machine; B B, the rods connecting the cross-head, which is not shown, with the cross-bar B'.

C is the crank-arm by which the cross-head is reciprocated from time to time, as the operator may require, through the cross-bar B' and the rods B B. The crank-shaft which drives the crank-arm C revolves continuously, so that the lower end of the crank-arm C reciprocates continuously between the slotted brackets b on the cross-bar B', the crank-shaft 35 being provided with a pin, c, which fits in the slots b' in said brackets. When the operator desires to reciprocate the cross-head, the block or dog D is moved forward under the end of the crank-arm, so that the crank-arm will 40 reciprocate the cross-bar B', and thus the cross-head. The dog D slides on a bed-plate, D', which is provided with a tongue, d, which fits into a corresponding groove or way, d', on the dog. The dog or block D is secured upon its bed by a screw or bolt, d', which fits into a longitudinal slot in the dog, and is screwed into the bed. The block D is moved forward 45 under the crank-arm by means of a treadle, E, which operates the bent lever F, pivoted to the frame of the machine at f, which actuates

the ratchet-bar G, the end of which engages with a pin, g, on the sliding block D. The lower or horizontal arm, f', of the bent lever F projects under the treadle E, or a projection, e', thereon, so as to be operated by the treadle 55 when the same is depressed by the foot. The treadle E is provided with a bent arm, e, to the end of which a spring, E', secured at one end to a frame, is attached, so as to automatically raise the treadle when the operator lifts 60 his foot therefrom.

H is a spring, secured at one end to the frame of the machine and at the other to the sliding block D, so as to retract said block from beneath the crank-arm the instant the treadle is 65 released.

H' is a secondary or auxiliary spring, attached at one end to the cross-bar B' and at the other to the sliding block D, so as to insure the retraction of said block in case the 70 spring G should accidentally be broken or fail to act.

I am aware that heretofore various levers, cams, and devices have been employed in heel-nailing machines for moving the sliding block 75 D both forward and backward; but such devices I have found from practical operation of the machines to be exceedingly liable to get out of order, and fail to retract the block D at the proper time, and thus occasion breakage and injury to the machine, as well as danger to the persons operating the same. By means of the spring the block D in my invention is always instantly retracted the moment the operator ceases to press upon the treadle, 80 so that there can be no danger of injury either to the machine itself or to the attendants operating it.

I claim—

1. The combination, in a heel-nailing machine, of the crank-arm C, the lower end of which reciprocates vertically within suitable guides, cross-bar B', connected with the cross-head of the machine, sliding block D, a treadle-and-lever connection for moving said block 90 under the crank-arm, and a spring connected with said block for retracting the same, said sliding block being of greater thickness than the length of stroke of the crank-arm, so that when said block is retracted by the spring 95 100

the crank-arm may reciprocate without operating the cross-bar and cross-head, substantially as specified.

2. The combination, in a heel-nailing machine, of the cross-bar B', provided with slotted brackets b, crank-arm C; provided with the pin c, reciprocating between said brackets, sliding block D, treadle E, provided with bent arms e, and spring E', bent lever F, provided with horizontal arm f', projecting under said treadle, ratchet-bar G, and springs H and H', for retracting said sliding block D, substantially as specified.

3. In a heel-nailing machine, the combina-

tion, with the crank-arm and cross-bar of the 15 machine, of the sliding block D, means for sliding and holding said block D under the crank-arm, and a spring for retracting the same, said cross-bar being provided with slotted brackets b, and said crank-arm having a pin, c, at 20 its end fitting in the slots of said brackets, substantially as specified.

Chicago, Illinois, December 7, A. D. 1883.

GEORGE F. CASS.
